United States Patent Office.

JOSEPH COGAN, OF CAMBRIDGE, MASSACHUSETTS.

Letters Patent No. 86,812, dated February 9, 1869.

IMPROVED HORSE-COLLAR.

The Schedule referred to in these Letters Patent and making part of the same.

To all whom it may concern:

Be it known that I, JOSEPH COGAN, of Cambridge, in the county of Middlesex, and State of Massachusetts, have invented an Improved Horse-Collar; and I do hereby declare that the following, taken in connection with the drawings which accompany and form part of this specification, is a description of my invention sufficient to enable those skilled in the art to practise it.

In that class of horse-collars in which enamelled leather, or "patent leather," is used to cover the rim and the front of the body-part of the collar, it is customary to stretch the enamelled leather over the frame, or stuffed rim, and body, stitching the parts of the covering in place as they are so stretched.

In making well-finished collars of this kind, it is necessary to use the best of enamelled stock, and even then the great stretching which the leather has to undergo, to avoid or remove all wrinkles, in connection with the bending necessary to bring all parts of it smoothly into place, often causes the enamel to crack, thereby materially injuring the value and durability of the collar.

The object of my invention is to so make an enamelled horse-collar that the enamelled surface will have to undergo no stretching to bring it into place; and I accomplish this by first completely forming the body and rim with a covering of common or unjapaned leather, stitching all the parts in place, and subsequently japanning the whole surface of the rim and body, covering every part, and filling the joints between the rim and body, and between the outer leather or facing of the collar and the wearing-piece, or that portion which comes directly against the breast of the horse.

It is in a collar so made and covered that my invention consists.

The drawing represents a section through the rim and body, at one side of the collar.

a denotes the rim;

b, the body;

c, the stuffing of the body; and

d, the stuffing of the rim.

e, the leather covering of the rim.

f, the leather covering of the body.

The rim and body of the collar having been formed or stuffed in the usual manner, each is surfaced with leather which is plain, or without any paint or enamel upon its wearing-surface, and which has therefore that pliability, flexibility, and capability of stretching found in common plain-finished leather.

The collar having thus been entirely finished, so far as construction or the direct work of the saddler is concerned, is then covered with successive coats of japan, or black varnish, *h*, care being taken to fill the thread-holes, and the joints between the rim and the body, and the collar is then baked until the coating is sufficiently dry and hard.

It will be obvious that, as all parts of the leather are brought into place before any enamel is applied to the surface thereof, there will be no tendency of the enamel to crack by strain upon it, or by bending; that a much smoother surface can be produced, as the collar is formed before the leather is rendered unpliant by its enamel; and that a much cheaper leather can be used in the construction of "patent-leather" collars, by making them in this manner.

As the joints are filled with the varnish, it will also be seen that such joints may be rendered impervious, and the whole collar water-proof, by this improvement.

I claim a horse-collar, having its rim and body enamelled, substantially as described.

JOSEPH COGAN.
